Primary Examiner — Cynthia R Underwood(74) *Attorney, Agent, or Firm* — Hooker & Habib, P.C.(57) **CLAIM**

The ornamental design for a hook support, as shown and described.

DESCRIPTION

FIG. 1 is a top right perspective view of the hook support;

FIG. 2 is a top view thereof;

FIG. 3 bottom view thereof;

FIG. 4 is a front view thereof;

FIG. 5 is a rear view thereof; and,

FIG. 6 is a right side view of the hook support shown in FIG.

1, with the left side view being a mirror-image.

The broken line portions of the figures are included to show unclaimed subject matter only and form no part of the claimed design.

1 Claim, 2 Drawing Sheets(56)
